UNITED STATES PATENT OFFICE

93,476

DESIGN FOR A PENCIL

Carl C. Harris, Orange, Mass.

Application July 16, 1934, Serial No. 52,596

Term of patent 7 years

To all whom it may concern:

Be it known that I, CARL C. HARRIS, a citizen of the United States, residing at Orange in the county of Franklin and State of Massachusetts, have invented a new, original, and ornamental Design for a Pencil, of which the following is a specification, reference being had to the accompanying drawing forming part thereof.—

Fig. 1 is a front view showing my new design;
Fig. 2 is an edge view, and

Fig. 3 is an end view of the same looking in the direction of the arrow as indicated on Fig. 1.

I claim:

The ornamental design for a pencil as shown.

CARL C. HARRIS.
